UNITED STATES PATENT OFFICE.

CHARLES M. COOK, OF ROCHESTER, NEW HAMPSHIRE.

SHOE-FASTENER.

1,348,392.

Specification of Letters Patent. Patented Aug. 3, 1920.

Application filed January 21, 1919. Serial No. 272,378.

To all whom it may concern:

Be it known that I, CHARLES M. COOK, a citizen of the United States, residing at Rochester, in the county of Strafford and State of New Hampshire, have invented certain new and useful Improvements in Shoe-Fasteners, of which the following is a specification.

This invention relates to shoes, and more particularly to fasteners therefor.

The object of the invention is to provide an improvement on what is known on the market as the "Plako" fastener, in which a slider is used to quickly open or close the shoe in connection with which it is employed.

Another object is to provide a combined tongue and slider holder constructed to hold the tongue against lateral movement and the slider against downward movement.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of the front portion of a shoe upper taken from the outside showing the slider for the closure in the act of being raised to operative closing position,

Fig. 2 is a rear elevation of the front portion of a shoe upper taken from the inside with the tongue in operative position and broken off to show its slider locking means carried thereby in operative engagement with the slider,

Fig. 3 is a horizontal section taken on the line 3—3 of Fig. 2, and

Fig. 4 is a view similar to Fig. 2 showing a slightly different application of the invention.

In the embodiment illustrated, a portion of a shoe upper U is shown having applied thereto the closure C known as the "Plako".

fastener, and which is operated by a slider 1 for opening and closing the shoe. A chain 2 is connected with the slider for operating it, and said slider has mounted thereon an aperture 3 which constitutes a part of this invention, and is designed to be engaged by a stud 5 which projects laterally from a plate 4, shown secured in Figs. 1, 2 and 3, to the shoe tongue T at its upper end. This plate 4 is fastened to the tongue by any suitable means, being here shown apertured and sewed to the tongue. When the closure is in the position shown in Fig. 2 for fastening the shoe upper, the stud 5 of plate 4 is entered into the aperture 3 of the slider 1 and operates to hold the tongue against lateral movement as well as to hold the slider against downward movement which oftentimes occurs, and thus accidentally unfastens the shoe.

In Fig. 4 the plate 4' carrying the stud 5' is carried by a flap 6 attached to the shoe upper at one side of the closure and which is designed to be engaged with the aperture 3 in the slider and holds said slider against release in the same manner as the plate 4 shown in the other figures does.

This device, while very simple in construction and cheap to manufacture overcomes the objectionable feature of the "Plako" fastener, and prevents much annoyance to the wearer.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the claimed invention.

Having thus fully described my invention, what I claim as new and desire to secure by Letters Patent, is:—

1. The combination with a shoe having a tongue, of a quick closing shoe fastener having a slider connected to operate it, a plate carried by the upper end of said tongue, and an aperture and stud, carried one by the plate and the other on the slider and adapt-

ed for interlocking engagement to hold the slider in elevated position and the tongue against lateral movement.

2. A shoe having a tongue with a plate secured to its upper end on its inner face, a stud extending laterally from said plate, a fastener for said shoe upper having a slider connected to operate it, said slider having an aperture to receive the stud on the plate

carried by the tongue, whereby the tongue is held against lateral movement and the slider against downward movement.

In testimony whereof I affix my signature in presence of two witnesses.

CHARLES M. COOK.
